APPARATUS FOR PUMPING OIL WELLS

Richard H. Carr, Chicago, Ill., and Kenneth A. Covell and Charles F. Terrell, Jr., Tulsa, Okla., assignors, by mesne assignments, to Sullivan Machinery Company, a corporation of Massachusetts

Application June 7, 1939, Serial No. 277,844

8 Claims. (Cl. 255—16)

Our invention relates to pumping apparatus, and more particularly to apparatus for pumping oil wells by means of the raising and lowering of sucker rods connecting a pump in the well to an actuating device, particularly one of the "beam" type, upon the surface. From another aspect, our invention relates more generally to devices for minimizing stresses between a source of reciprocating motion and devices reciprocated thereby.

For the pumping of oil wells of considerable depth "beam" well pumping is by far the most common method used. This method is, as has long been recognized, subject to serious difficulties, however, as rod breakage is very common and the resultant pulling and replacement expense may be serious. Peak loads imposed upon the rods with this type of pumping device are high. The stress range is comparatively great. The power consumption is also more than would be requisite to do the useful work accomplished. And the relative positiveness, so to speak, of the whole system contributes seriously to the reduction in sucker rod life.

It is an object of our invention to provide an improved pumping system. It is another object of our invention to provide an improved pump-actuating apparatus. It is a further object of our invention to provide an improved device for reducing sucker rod peak loads and stress ranges in beam type pumping systems. It is a still further object of our invention to provide an improved arrangement for minimizing stresses between a source of reciprocating motion and the device reciprocated. Other objects and advantages of our invention will hereinafter more fully appear.

In the accompanying drawings, in which for purposes of illustration an illustrative embodiment and several modifications of our invention have been shown—

Fig. 1 is an elevational view, in somewhat diagrammatic form, of a pumping system in which the preferred embodiment of the invention is incorporated.

Fig. 2 is an enlarged vertical sectional view, on the plane of the line 2—2 of Fig. 1, through the shock-reducing cylinder and piston mechanism of the preferred embodiment.

Fig. 3 is a view similar to Fig. 2 but showing the parts in different relative positions.

Fig. 3a is a detail sectional view showing a modification of the structure shown in Figs. 2 and 3.

Fig. 4 is an enlarged vertical section on a plane corresponding to the plane of Fig. 2, showing a modified form of shock-absorber cylinder and piston mechanism.

5 Fig. 5 is a view similar to Fig. 4, showing the parts of the device of that figure in different relative positions.

Fig. 6 is an enlarged vertical section on a plane corresponding to the plane of Fig. 2, showing a 10 further modified form of shock-absorber cylinder and piston mechanism.

Fig. 7 is a view similar to Fig. 6, showing parts of the device of Fig. 6 in different relative positions.

15 Fig. 8 is a diagram showing superimposed on each other dynagraph cards with and without the use of an embodiment of our invention.

In the accompanying drawings, referring first to Figs. 1, 2, 3 and 8, it will be noted that the 20 polished rod 1 arranged at the top of the sucker rod line (not shown) in the well, whose casing head is indicated at 2, is actuated by "beam" type pumping apparatus generally designated 3. The pumping apparatus 3 illustrated includes a Samson post 4, a walking beam 5, and a pump driving unit 6 of conventional form connected by a pitman 7 with the walking beam and driven in any suitable manner. A beam hanger 8 serves to support a mechanism generally designated 10, hereinafter more fully described, for the purpose of reducing peak loads and rod stresses; and this mechanism 10 is connected through a suitable clamp mechanism 11 to the polished rod line 1.

Referring now more particularly to Figs. 2 and 35 3, it will be noted that the apparatus 10 comprises a cylinder 12 having a top head 13 and a bottom head 14, the heads and cylinder being held in assembled relation by any suitable means, such as the tie bolts or rods 15. Within the bore 40 16 of the cylinder is a piston 17 provided with a piston rod 18. The piston rod 18 is connected by the clamp mechanism 11 with the polished rod 1, while ears 19 carrying a pin 20 serve to provide a pivotal connection between the beam hanger 8 and the apparatus 10. The lower head 14 is provided with a suitable gland 22 and packing 23 to preclude leakage of pressure downwardly along the piston rod 18 from the space below the piston 17. The upper end of the cylinder bore 16 is provided with a port 24 continuously connecting the interior of the cylinder with the atmosphere except when the piston 17 in certain upper positions thereof closes the port 24. The port 24 is arranged a suitable distance below the upper end

45 50 55

40 45 50 55

of the cylinder 12 so that there will be assured a definite cushioning action as the piston 17 approaches the upper cylinder head 13. When the top of the piston 17 is above the upper edge of the port 24 air will be entrapped in the top of the cylinder bore 16, and the relative approach to each other of the head 13 and piston 17 will be suitably cushioned. The port 24 permits breathing of the cylinder on relative separation between the piston 17 and the top cylinder head 13 as soon as the port 24 is uncovered.

Means is provided for maintaining a comparatively high pressure beneath the piston at all times during normal pumping, but one (a pressure) which will not fluctuate very substantially upon relative movement of the piston 17 and the cylinder 12 varying the distance between the piston 17 and the lower cylinder head 14. To this end there is provided a lateral opening 27 spaced a sufficient distance above the bottom of the cylinder to provide a cushion should the air pressure that normally keeps the piston 17 and the lower cylinder head 14 apart suddenly be vented. The opening 27 is connected by a suitable flexible conduit 28 of large flow area, with an appropriate source of pressure, later to be described but which may be noted in passing to be of such large volume that relative movements between the cylinder 12 and piston 17 will not cause material fluctuations in pressure.

In view of the maintenance of a comparatively high pressure below the piston 17 and a pressure above the piston, when the piston 17 is remote from the head 13, substantially equal to atmospheric pressure, it is evident that there may be some leakage past the packing rings 29, but such leakage will immediately be vented through the port 28.

To supply pressure to the opening 27 any suitable means may be employed. And we herein disclose as illustrative of any suitable initial source of high gaseous pressure a compressor 35 driven by any suitable means, herein diagrammatically represented by the belt 36. This compressor is of the comparatively high pressure type and capable of pumping to a pressure of 250 pounds or more, and may desirably be multi-stage in construction. Its discharge line 37 is provided with a relief valve 38 and is connected through piping 39 with a tank 40, which may be termed, for convenience, an unloader tank. The tank 40 is connected by a line 41 to a pilot valve 42 controlling any suitable type of unloading means (not shown in detail) for the compressor 35.

The unloader tank 40 is connected through a suitable reducing valve 43 with a line 44 which extends to a point adjacent the top of the Samson post 4 and which is there connected by a flexible hose 45 with a clearance tank or receiver 46 of relatively large volume compared with the cylinder 12 and suitably mounted upon the top of the beam 5.

If desired, an auxiliary control of the pressure supply system may be provided, as at 47, utilizing a pressure switch of any suitable conventional type receiving air pressure from a point beyond the pressure reducing valve 43 and controlling a circuit to an electric driving motor for the belt 36, and starting said motor whenever the pressure in the line 44 falls below a desired minimum value, and stopping it upon an increase to a desired maximum value. It will be evident that the nature of the controls and even of the

type of pressure source may be widely varied within the scope of our invention.

It is important, in order that the stresses imposed on the sucker rod line shall not be great, that while the apparatus 10 must provide for the transmission of a sucker rod raising force adequate to raise the rods under all circumstances, yet there should be a yielding within the device 10 which will preclude the transmission of excessive pressures to the sucker rod line. It is therefore important that relative separation of the piston 17 and the upper cylinder head 13 shall not be attended by the building up of a high pressure through the compression of the fluid below the piston; and for this reason the receiver 46 is made of very substantial volume and will have its conduit 28, through which it is connected to the cylinder 12, of substantial flow area, so that upward movement of the cylinder 12 at a faster rate than the upward movement of the piston 17 shall not be able to cause the building up of a substantially higher pressure than prevails during down strokes beneath the piston 17. It will be understood that by the proper predetermination of the pressure within the beam receiver 46 and the effective cross sectional area of the piston 17, the device 10 may be caused to be certain to possess the capacity to raise the full load of the sucker rods and the oil without the necessity of the piston resting on the lower head 14; while by appropriately proportioning the pipe 28 and the receiver 46 the avoidance of excess stresses may be realized.

It will be evident that under the action of gravity the piston 17, unless prevented, might, with the apparatus shut down and the air pressure reduced through leakage or otherwise, assume a position resting upon the bottom cylinder head 14. If the pressure in the receiver tank 46 be built up a sufficient time before the apparatus is put in operation, leakage downward past the rings 29 would ultimately produce a pressure below the piston sufficient to uncover the port 27; and thereupon the piston would promptly move to approximately the position shown in Fig. 3. If it is not desired to depend upon leakage past the rings, other expedients might be resorted to, either to prevent the piston from assuming a position relative to the cylinder in which the port 27 would be covered, or to permit very quickly a temporary initial delivery of fluid to the bottom of the cylinder bore 16. As one mode of assuring the presence of pressure beneath the piston 17 there might be mentioned the employment of a rod clamp such as is shown at 34 in Fig. 1. This rod clamp could be applied temporarily or permanently, as desired, to the polished rod at a position thereon in which it would prevent downward movement of the piston 17 relative to the cylinder 12, below a position in which in the lowest position of the lifting end of the beam the cylinder 12 will not have its pressure supply opening 27 at least partially below the lower edge of the piston. Of course as soon as adequate pressure is built up beneath the piston there will be no further movement of the piston downward again, so long as the system operates normally, far enough to permit engagement of the rod clamp 34 with the stuffing box or any special abutment that may be provided for engagement thereby, to limit the downward movement of the polished rod and the parts connected thereto. As may be more clearly apparent following a discussion, which will shortly be presented, of the mode of operation of this device, when the cylinder 12 is

Just attaining its lowest position the piston 17 will ordinarily be in its highest position in the cylinder 12, and thus there will be no tendency for the rod clamp ever to contact the stuffing box or other abutment means therefor during normal pumping.

In Fig. 3^a there is shown a bypass 49 opening through the lower head 14' and having a manually operable stop valve 50 between its ends for conducting at will fluid from the conduit 28 directly to the bottom of the cylinder bore 16. If it is not desired to use a rod clamp or to rely on leakage past the rings 29, this arrangement shown in Fig. 3^a will permit, by the opening of the valve 50, the delivery of high pressure fluid substantially instantly beneath the bottom of the piston 17, and the raising of the latter above the port 27; and as soon as the piston has been raised above the port 27 the manually operable valve 50 can be immediately closed and the presence of a cushion at the bottom of the cylinder assured.

If it be assumed that in Fig. 1 the beam is stationary and that air has been delivered in some way beneath the piston 17, then the positions of the clamp mechanism 11 and the rod clamp 34 would be approximately in proper relation to the cylinder 12, and the piston 17 in about the position of Fig. 3 to the cylinder 12.

The mode of operation of the structure so far described will be self-evident. At the beginning of each full upward movement of the right-hand end of the beam 5 the piston 17 will be adjacent the top of the cylinder 12. By the time the beam has assumed a horizontal position the piston 17 will have lagged behind the cylinder a substantial amount. By the time, however, when the right-hand beam end reaches its uppermost position, the piston 17 will again be adjacent the top of the cylinder. On the down stroke of the right-hand end of the beam the piston 17 will of course remain adjacent the top of the cylinder 12, as the pressure below the piston will be more than adequate to support the weight of the rods on the down stroke.

Now, the mode of operation of the whole system may be briefly described. Before starting up the beam, the compressor 35 will be operated to build up the pressure in the system to the required value, and through the excess of pressure beneath the piston the latter will be raised to approximately the position shown in Fig. 3. The beam may then be placed in normal operation, and from then on the pressure is automatically maintained by the compressor control system. With a suitable pressure in the system the piston 17 will remain adjacent the top of the cylinder 12 at all times except when the rod load exceeds the supporting force of the air under the piston. When the rod load increases above the supporting force of the air, the cylinder will continue to move upward at the same rate as the beam, but the piston movement will be retarded, and so the cylinder will move upwardly more rapidly than the piston. The amount of relative movement will depend upon the pressure carried in the clearance tank, the volume of the latter, and the magnitude of the well load.

Because of the selected ratio to the sucker rod line load of the product of the pressure below the piston and the area of the piston, when the line tension tends to increase, the pressure under the piston will be ineffective to sustain the load, and the cylinder moves upwardly relative to the piston until the point in the stroke of the beam is reached where the tendency of line tension to in-

crease is passed. In this manner, peak loads which are encountered in conventional beam pumping are avoided. The piston will be adjacent the top of the cylinder at the beginning and at the end of each up stroke, but will be at some lower position during the range of high peak loads occurring in the middle of the up stroke. On the down stroke the piston will of course remain adjacent the top of the cylinder, as the pressure carried will overcome the weight of the rods on the down stroke.

From the foregoing description, it will be evident that we have provided an apparatus which will greatly reduce the rod loads and which will, further, substantially reduce the stress range in the rods. There will also be a reduction in the power required to operate the pumping system.

Before describing the other modifications of the invention which are herein disclosed for purposes of illustration, reference may be made to Fig. 8, in which there is shown a pair of typical dynagraph cards superimposed upon each other, one reproduced in heavy line and one in lighter line, the card in light line showing the results obtained with a solid connection between the beam line and the polished rod, and the one in heavier line corresponding to the card obtained with the use of our present invention. It should be pointed out that the latter card was not made with a device corresponding exactly in all details to the illustrative embodiment which has been hereinabove described, and the lighter card was also not made with a beam type pumping apparatus corresponding precisely in dimension to the one shown. However, these cards will serve to depict fairly the comparative results of the use of our invention, and the actual structure used in the production of the heavy-lined card embodied in our invention.

It will be observed that there was a reduction of between 26 and 27% in the peak load, and there was a reduction of more than 33% in stress range, through the use of a yielding connection between the beam and the polished rod. The maximum rod stress was reduced from 31,750 pounds per square inch at the time and place these cards were produced, through the use of the yielding connection between the polished rod and beam, to 23,250 pounds per square inch. The polished rod horsepower was reduced from 36.3, in the particular test made, to 29.6.

It will be observed that by somewhat increasing the pressure below the piston 17 a reduced relative motion between the piston and cylinder is obtainable, but that this results in a higher rod load. In general it has been observed that the more the pressure is lowered, within limits, below the piston 17, and the greater the relative piston motion, the lower the maximum polished rod load, the greater the load reduction, the lower the rod stress in pounds per square inch, and the lower the stress range. At any given installation the pressure utilized will be determined to provide the best results for the particular conditions encountered.

Referring now to the embodiment of the invention shown in Figs. 4 and 5, it will be observed that there is a general correspondence between the structure of these figures and that of Figs. 2 and 3 and corresponding parts have been given like numbers. There is a cylinder 12 having an upper head 13 and a lower head 14, and suitable holding means 15 holding the heads and cylinder in assembled relation. The piston 17, which is reciprocably arranged within the bore 16 of the

cylinder 12, differs somewhat in proportion and in construction from the piston 17. It will be observed that herein the piston 17' is shown somewhat longer than the piston 17 and is surrounded between its ends by an annular groove 51 connected to atmosphere by a radial passage 52 and a passage 53 extending longitudinally through the piston rod 18', and having a vent port 54 opening to atmosphere through the wall of the piston rod at a point which is never covered by the gland 22 associated with the lower head 14. A lateral port 27 and a breather port 56 open through the walls of the cylinder at points spaced, respectively, from its lower and upper ends. The breather port 56 is arranged in such relation to the upper head 13 of the cylinder 12 that in the uppermost position of the piston 17' the annular groove 51 never attains to communication with the port 56; and the groove 51 never attains communication, in the lowermost position of the piston 17', with the port 27. The port 56 is not at all times in free communication with the atmosphere, but instead is provided with a check valve device 57 having a swinging valve element 58 therein. The valve 58 is of the inwardly opening type. It will be evident that if the valve 58 were to become closed and the pressure above the piston 17' were to build up through leakage past the rings 29 upon the piston, there would, in the absence of the annular groove 51 and the venting means provided therefor, build up in time such a pressure above the piston as to preclude the intended mode of operation of the device. However, any leakage of fluid upwardly from the comparatively high pressure space below the piston 17' past the rings 29 is prevented from tending to equalize the pressure above and below the piston, since as soon as the fluid passing upwardly between the piston and cylinder walls attains to the groove 51, it is immediately vented through the passages 52 and 53 and the port 54.

The mode of operation of this device can be readily understood, for it will be appreciated that the port 27 is connected by a suitable connection 28 with a receiver tank corresponding to the tank 46 of Fig. 1.

The disposition of the port 56 at a definite distance below the upper head 13 of the cylinder makes certain the existence of a definite cushioning action under all circumstances, as there is relative approach between the head 13 and the piston 17'; and even were the valve mechanism 57 not to function as intended, there would be a positive entrapment of air during at least the last portion of the relative upward movement of the piston within the cylinder. The valve 57, as has been noted, is of a type adapted to let in air to, but to hinder escape of air from, the upper end of the cylinder. Obviously, on relative separation of the head 13 and the piston 17', when the pressure within the space above the piston becomes materially less than atmospheric, the valve mechanism 57 will permit air to enter the upper end of the cylinder; and the pressure at the upper end of the cylinder will not exceed the value which will be attained by the compression of the air that will enter the upper end of the cylinder when the piston 17' is at its maximum distance from the head 13.

It will be understood now that upon the attainment of air at the pressure within the tank 46 beneath the piston 17', the latter will be moved upward to approximately the position shown in Fig. 5. Then during the lifting stroke of the beam, with resultant raising of the cylinder 12,

there will be, during a portion of the upward travel of the cylinder, a movement of the latter upwardly relative to the piston and the taking in of a small quantity of air, ordinarily, through the check valve device 57 into the space above the piston. As the upward movement of the cylinder slows down, as the right end of the beam approaches its uppermost position, the piston will overtake, so to speak, the cylinder and there will be a somewhat greater cushioning than in the form of the invention first described, due to the presence of the check valve device 57. With this exception—and it will be understood that any change in proportions which may be occasioned by this difference in cushioning action will be duly made—the general mode of operation of the structure of Figs. 4 and 5 will be the same as that with the structure of Figs. 2 and 3. It is therefore believed unnecessary to describe in further detail the specific operation of this embodiment of the invention.

In Figs. 6 and 7 still another embodiment of certain aspects of the invention is shown. In this embodiment parts corresponding generally to parts in Figs. 2 and 3 and/or Figs. 4 and 5 are indicated by reference characters which are double primed, and corresponding parts are indicated by like reference characters. The essential difference, aside from a somewhat shortening of the piston 17'' from what is shown in Figs. 4 and 5 (this shortening being made possible by reason of the fact that the lateral fluid supply opening 27 is omitted), resides in the embodiment of a bottom connection instead of a side connection between the tank 46 and the lower end of the cylinder. It will be observed that the side connections 27 are replaced by a passage 60 opening directly through the bottom of the cylinder's lower head 14', and the connection 28 enters the head of the cylinder and communicates with the port 60 instead of being connected to the side of the cylinder proper.

A detailed description of the mode of operation of this species of the invention is not necessary, because a full understanding will be had by simply noting the fact that there is no dashpot type cushioning with this embodiment of the invention possible at the lower end of the cylinder, because the elimination of the side connection with the tank 46 and the substitution of the bottom passage 60 do not permit the complete entrapment of fluid beneath the piston 17'', no matter how far down the latter moves in the cylinder. On the other hand, no special provision of any kind, and no delay while waiting for leakage past the rings to build up the requisite pressure below the piston 17'', are necessary.

From the foregoing description of the various embodiments of our invention from its structural aspects, it will be apparent that we have provided simple and highly practical devices for the purposes set forth, some possessing certain advantages and others others; that these devices reduce the peak polished rod loads; that they reduce polished rod horsepower; reduce stress range; and do not result in any loss of stroke, because the relative position of the pistons 17, 17' and 17'' and their respective cylinders 12 to each other is the same at the beginning and at the end of the lifting movement of the walking beam. Moreover, there is a great reduction in the breakage of sucker rods and the expense which follows this serious event. It is estimated, based on experience to date, that rod partings may be reduced by ninety percent, and the ex-

pense for rod servicing jobs reduced to one-tenth of the cost previous to the installation of our invention. It will also be observed that we have provided improved means for connecting sources of reciprocating motion with devices to be reciprocated, possessing marked advantages.

While we have in this application specifically described several embodiments which our invention may assume in practice, it will be understood that this structure is shown for purposes of illustration, and that the invention may be modified and embodied in various other forms without departing from its spirit or the scope of the appended claims.

What we claim as new and desire to secure by Letters Patent is:

1. In an apparatus of the nature described, a cylinder, a piston therein, a connection with a substantial volume of gaseous fluid under pressure exceeding atmospheric opening through the side of the cylinder at a point spaced from one end of the latter, and a lateral opening communicating with atmosphere for the influx and discharge of fluid spaced from the other end of the cylinder a distance less than the length of said piston.

2. In an apparatus of the nature described, a cylinder, a piston therein, a connection with a substantial volume of gaseous fluid under pressure exceeding atmospheric opening through the side of the cylinder at a point spaced from the bottom of the latter less than the length of the piston, and a lateral opening communicating with atmosphere for the influx and discharge of fluid spaced from the top of the cylinder less than the length of said piston.

3. In an apparatus of the class described, a cylinder having a piston movable therein and dividing the interior of said cylinder into spaces that change in volume on relative movement between the cylinder and piston, said cylinder and piston having provision for the connection of one of them to a sucker rod line and of the other of them to a walking beam, means for subjecting the space within said cylinder which diminishes in volume during raising of the sucker rod, to a pressure, and means for precluding leakage of said pressure past the piston to the opposite side of the latter, including a peripheral groove in the piston and means for venting said groove to the exterior of said cylinder.

4. In combination, a beam-type pumping apparatus, a sucker rod line, and a load-limiting connection between the beam and the sucker rod line including means forming an expandable chamber containing an expandable fluid through which lifting force is exerted on said sucker rod line, and means for confining so relatively large a volume of expandable fluid under pressure in such substantially free communication with said chamber that any diminution of the size of said chamber during lifting by said beam will not largely increase the chamber pressure, said ex-

pansible chamber having a communication with said confined volume of fluid subject to interruption of flow from the former to the latter automatically in the event of diminution of said chamber size below a predetermined minimum.

5. In an apparatus of the character described, the combination with a member to be reciprocated and a walking beam for reciprocating said member, of a pneumatic shock absorber pivotally suspended from the operating end of said beam and operatively connected to said member to be reciprocated and comprising a fluid cylinder containing a reciprocable piston and means for controlling the pressure of the fluid in the ends of the cylinder at the opposite sides of said piston, said pressure-controlling means including a source of high pressure fluid communicating with the cylinder at the lower side of said piston, and means including passage means having check valve means associated therewith for controlling the supply of fluid at atmospheric pressure to the space within the cylinder at the upper side of said piston, the points of communication of said high pressure fluid source and said passage means with said cylinder being spaced from the ends of said cylinder to provide cushioning spaces for said piston.

6. In an apparatus of the character described, a cylinder, a piston therein, a connection with a substantial volume of fluid continuously under pressure exceeding atmospheric and opening through the side of the cylinder at a point spaced from the bottom of the latter less than the length of the piston, valve controlled passage means for placing said pressure volume in communication with the bottom of said cylinder, and an opening communicating with atmosphere for the influx and discharge of fluid to the top of said cylinder.

7. In an apparatus of the character described, relatively reciprocable cylinder and piston elements; a connection with a substantial volume of fluid continuously under pressure exceeding atmospheric opening through the side of the cylinder element at a point spaced from one end thereof but in such proximity to said end that when said piston is at said end it completely occludes said side opening, and an opening communicating with atmosphere for the influx and discharge of fluid relative to the other end of said cylinder.

8. In an apparatus of the nature described, a cylinder, a piston therein, a connection with a substantial volume of gaseous fluid under pressure exceeding atmospheric opening into one end of the cylinder, and a lateral breather opening in the cylinder adjacent to but spaced from the other end thereof, said opening being spaced in its entirety a distance less than the length of said piston from the other end of said cylinder.

RICHARD H. CARR.

KENNETH A. COVELL.
